UNITED STATES PATENT OFFICE.

MARY ETTA COWLES HOPKIRK, OF AGENCY, IOWA.

HAT-PROTECTOR.

SPECIFICATION forming part of Letters Patent No. 357,200, dated February 8, 1887.

Application filed April 10, 1886. Serial No. 199,347. (No model.)

To all whom it may concern:

Be it known that I, MARY ETTA COWLES HOPKIRK, of Agency, in the county of Wapello and State of Iowa, have invented a new and Improved Hat-Protector, of which the following is a full, clear, and exact description.

My invention relates to hat-protectors intended particularly for covering ladies' head-wear, and has for its object to provide a simple, inexpensive, portable, and readily-adjustable device of this character which may be quickly applied to and removed from a hat or bonnet without injuring its delicate trimmings, and may be adjusted to fit small or large hats with facility.

The invention consists in certain novel features of construction and combinations of parts of the hat-protector, all as hereinafter fully described and claimed.

Reference is to be had to the accompanying drawings, forming a part of this specification, in which similar letters of reference indicate corresponding parts in all the figures.

Figure 1 is an under side view of the hat-protector in open condition. Fig. 2 is a vertical sectional elevation of the protector with the extension or enlarging piece attached and drawn in at the lower edge as when in use, and Fig. 3 is an inside face view of a portion of the extension-piece.

The main body portion A of the hat-protector, which alone will be used to cover hats of small or medium size, consists of a piece of some light water-proof fabric—such as rubber cloth, oiled silk, or the like—and preferably bound around the margin at the inside with a facing, a, of some suitable fabric, adding strength to the water-proof material of the covering.

At the inner face of the body fabric A, I secure, in any suitable manner, a couple of narrow strips, B B, of suitable fabric, forming casings through which draw strings or tapes C C are run.

At opposite edges of the facing a are attached series of small rings, D E, respectively, through either series of which rings a cord or draw-string, as at F, may be passed and then drawn up and tied, as presently explained.

The extension-piece G of the hat-protector consists of an endless strip or band of light water-proof fabric, like that of the body fabric A, and preferably hemmed over or provided

at opposite edges at the inside with bindings or facings g g, to which are attached the series of rings H I, respectively, through which cords 55 may be passed.

When the protector is to be used on a small or medium sized hat or bonnet, the draw-strings C will be tightened more or less to conform the body A of the protector somewhat to the size 60 and shape of the hat, and the strings C will be tied. The draw-string F having been adjusted in the marginal series of rings D, the protector fabric A will be laid gently over the hat or bonnet, and the string F will then be drawn 65 up and tied to hold the protector to place.

To apply the protector to a large hat or bonnet, the draw-strings C will be properly adjusted and tied, and the draw-string F will be removed from the rings D of the body A of the 70 protector, and will be run through the series of rings I at one edge of the extension-piece G, and another draw-string, J, will be run through the inner series of rings E on the body fabric A, and also through the series of rings H at 75 the upper edge of the extension-piece G, the rings E H being of like number, and whereby, when the string J is drawn into the proper size and tied, the extension-piece G will be held to the body part A, and the latter will overlap 80 the piece G all around for a distance equaling the space between the two series of rings D E, or about the width of the facing a, or for a sufficient distance to prevent rain and snow from beating through at the top of the piece 85 G onto the hat or bonnet, over which the protector thus arranged will be placed, whereupon the draw-string F, now in the rings I, will be drawn upon and tied, as indicated in Fig. 2, to hold the enlarged protector securely over 90 the hat or bonnet.

There may be but one draw-string C, or more than two, fitted into casings in the body fabric A, as the size of the latter may require; but two, as shown, will ordinarily be used.

It is obvious that a hat-protector made with draw-strings at its inner face around the crown—and after the strings are properly adjusted to shape the crown of the protector—may be applied over a hat without danger of crushing 100 frail trimmings on the hat, which would not be possible with protectors intended to be applied over a hat prior to tightening up and tying a single marginal draw-string. Furthermore,

the marginal rings, through which the fastening draw-string F is run, allow the string to be tightened easily and quickly without twisting the protector around on top of the head-wear, and whereby damaging strains on the hat-trimmings are avoided, which would not be the case if a string or elastic were used within a draw-casing. Furthermore, by placing the draw-strings C within the casings B on the body part A of the protector, the draw-strings will not be liable to catch upon and injure delicate trimmings when the protector is removed from the hat, as will readily be understood.

Having thus fully described my invention, what I claim as new, and desire to secure by Letters Patent, is—

1. A hat-protector made with an imperforate body portion formed from flexible water-proof fabric, and with draw-strings applied around the crown of the protector upon its inner face, substantially as herein set forth.

2. A hat-protector made with an imperforate body portion formed from flexible water-proof fabric, and with draw-strings applied around the crown of the protector and within casings secured upon the inner face of the protector, substantially as and for the purposes herein set forth.

3. A hat-protector made with an imperforate body portion formed from flexible water-

proof fabric, and provided with marginal rings to receive a fastening draw-string, substantially as herein set forth.

4. A hat-protector made with a body portion, A, formed from flexible water-proof fabric, and provided with draw-strings, as at C, around the crown, and with marginal rings, as at D, to receive a fastening draw-string, substantially as herein set forth.

5. A hat-protector made with a body portion, A, having a series of rings, E, within its margin, and with an extension-piece, G, provided with rings H I at opposite edges, a draw-string, J, uniting rings E H, and a fastening draw-string, as at F, passed through rings I, substantially as herein set forth.

6. A hat-protector made with an imperforate body portion, A, formed from flexible water-proof fabric, and provided with crown draw-strings C and two series of marginal rings, D E, and with an extension-piece, G, provided with rings H I at opposite edges, a draw-string, J, uniting rings E H, and a fastening draw-string, as at F, passed through the rings I, substantially as and for the purposes herein set forth.

MARY ETTA COWLES HOPKIRK.
